Inventor:

Arthur L. Rossberg,

By his Attorney,

Horace Barnes,

FIG 7

UNITED STATES PATENT OFFICE.

ARTHUR L. ROSSBERG, OF PORTLAND, OREGON.

ANGULARLY-ADJUSTABLE TOOL HOLDER.

Application filed December 26, 1924. Serial No. 757,976.

To all whom it may concern:

Be it known that I, ARTHUR L. ROSSBERG, a citizen of the United States, residing at Portland, in the county of Multnomah and 5 State of Oregon, have invented certain new and useful Improvements in Angularly-Adjustable Tool Holders, of which the following is a specification.

This invention relates to improvements 10 in combination tools, and particularly to that type wherein the holder for the tool selected may be adjusted angularly with respect to the operating shank.

The object of my invention is to provide 15 a tool-holder of simple, serviceable and economical construction that may be adjusted and set at any angle relative to the operating handle thereof within an arc of ninety degrees and wherein the tool may be rotationally actuated in any of its angular set positions with full power and efficiency.

Further objects and advantages of the invention and objects relating to particular details of construction will be fully described 25 and readily apparent in the detailed description to follow.

The accompanying drawings illustrate by way of example one form of the invention, in which:

30 Figure 1 is a view in side elevation of an embodiment of my invention.

Fig. 2 is a partial view of the same on an enlarged scale with one of its outer walls shown in longitudinal section.

35 Fig. 3 is a view in side elevation of the device with the outer frame cut away illustrating the intermeshing elements in longitudinally aligned condition taken on line 3-3 of Fig. 2.

40 Fig. 4 is a similar view showing the same devices disposed at an angle of ninety degrees.

Fig. 5 is a fragmentary view similar to 45 Fig. 3 showing the opposite side of the device, taken on line 5-5 of Fig. 2.

Fig. 6 is a partial view in longitudinal section of the tool-holding means.

Fig. 7 is a view in cross section on line 7-7 of Fig. 2.

50 Referring to said views, the reference numerals 1 and 2 indicate complementary steel barrels of substantially identical construction each having a cylindrical portion 3 and an inwardly disposed squared portion 5.

55 Said cylindrical portions are formed with a cylindrical bore 6 and the squared

portions are each chambered, as at 7, communicating with said bores. One side of each said chamber is open toward the side in which the barrels relatively flex, while 60 the rear wall 8 and side walls 9 and 10 are in rectangular relation. The opposite side walls 9 and 10 are extended outwardly of the rear wall and are formed with aligned screw-threaded holes 11 in their transverse 65 axes. Said outer edges of the side walls are formed in arcs having the holes 11 as their centers and are formed with gear-teeth 12 upon one side 9 arranged to intermesh and upon the other side 10 the inner marginal 70 edge is beveled, as at 13.

A frame 14 adapted to hingedly connect said barrels is composed of an integral back 15 and side-plates 16 and 17 at right angles thereto adapted to overlie said rear wall 75 and side walls of the barrels, respectively, the side-plates 16 and 17 are provided with spaced holes 18 disposed to register with the respective holes 11 in the chamber-walls. Screws 19 extend through the holes 18 where 80 they are provided with a circular shoulder 20 and are threaded into the holes 11 to secure the barrels 1 and 2 together in an articulated joint which will admit of a relative flexure of ninety degrees.

Upon each side of the gear-teeth 12 angularly directed stops 21 are provided which limit the movement of the outer barrel 2 from a longitudinal extension of the barrels to a ninety degree angle. A screw 22 is 85 threaded in the side-plate 16 and is formed with a tapered head 23 on its inner end adapted to bear against the beveled edges 13 and thereby clamp the barrels to the frame at any set position desired.

Within the bore 6 of the barrel 1 a cylindrical spindle 24 is rotatably mounted having an integral flange 25 at its outer end bearing upon the outer end of the cylinder 3. The operating shank 26 of the 100 holder is rigidly keyed or pinned axially within said spindle. Said spindle is bifurcated at its inner end providing two spaced ears 27 each formed with a bearing aperture 28 in the same transverse plane as the pivot-screws 19.

A similar spindle 29 is rotatably mounted in the barrel 2 and formed with a flange 30 analogous to the flange 25 and with spaced ears 31 apertured at 28 in the plane 110 of the screws 19 upon the outer end of the joint connection between the frame 14 and

the barrel 2. Spindle 29 is further formed with a tubular socket 32 terminating at its inner end in a squared recess 33. A tool, such as a screw-driver 34 provided with a round shank 35 and a flattened end 36 to extend within said recess is seated in said socket.

A universal joint is formed at the ends of each said spindle co-acting with a link 37 disposed within the chambers 7 and intermediate said spindles. Said link consists in a medial body and a pair of spaced stems 38 directed in opposite directions from said body and arranged to extend between the ears 27 and 31, respectively. A rectangular block 39 is pivotally connected by pins 40 with each of said pair of ears through the apertures 28 and upon intermediate side of the block is similarly connected by pins 41 with the stems 38 of the link 37. A universal joint is thereby afforded at each end of the link in the transverse plane of the hinge connection between the frame and the barrels whereby rotary motion may be transmitted to the tool from the shank 26 at whatever angle they may be disposed.

The provision of the barrels intermeshing through the teeth 12 intermediate the transverse axes of the universal joints at each end of the link 37 and the pivotal connections of the barrels with the frame ensures a true alignment of the barrel-pivots with the joints of the power-shaft including the shank 26, the spindles, the link, and the universal joint at each end thereof.

The device is very simple and strong in

construction and may be employed in a wide variety of uses. Any sort of tool adapted to function with rotary motion may be used, such as a screw-driver, socket-wrench or reamer. It has obvious advantages in its adaptability in reaching screws or nuts otherwise inaccessible or it may be utilized as a straight screw-driver and in which use it is extremely handy as the tool may be held upon the screw by one hand grasping the barrels and frame to steady it while the other hand is free to exert full power upon the handle 42 without danger of dislodging the tool from the screw.

Having described my invention, what I claim, is:

A tool-holder, consisting in a pair of barrels each including a cylindrical portion having a bore therethrough and a rectangular chambered portion, said chambered portions having intermeshing gear-teeth upon one side and arcuate beveled edges upon their opposite sides, a frame having side-plates overlying the side walls of said chambered portions having pivotal connections therewith, a screw threaded in one of said side-plates having a tapered head bearing upon said beveled edges of the chambered portion, spindles rotatively mounted in the respective bores of said barrels, and universal-joint connections between said spindles having their axes in the transverse planes of said pivotal connections, respectively.

ARTHUR L. ROSSBERG.
